COEXTENSIVE ROOM SYSTEM WITH
MECHANICAL CONVEYERSCharles R. Hughes, Altoona, Pa., assignor to
Albertine M. Hughes, Altoona, Pa.

Application June 29, 1933, Serial No. 678,268

5 Claims. (Cl. 262—1)

The invention relates to improvements in the art of mining, more particularly a combination of a mine plan and a conveying system, an object being to operate a system of mechanical material handling apparatus in a plan of headings and rooms especially laid out to permit efficient and cheap extraction of the mineral.

The immediate object is to extract coal by the use of especially designed mechanical conveyors operating in a system of chambers, which system is neither a room-and-pillar system in its usual meaning, nor a long-wall system, nor a panel system, but rather a modified room-and-pillar system.

15 A further object is to locate the rooms of the present system parallel to and co-extensive with the heading serving them, thereby being distinguished from the room-and-pillar system, as it is usually known, wherein the rooms are turned off the heading in a direction transverse or angled thereto. For lack of a better name the system will be referred to hereafter as a "co-extensive room system", the name "room-and-pillar-system" being reserved for its usual meaning.

20 In coal mining, the terms "heading" or "entry" and "room" have different meanings and signify chambers of different types and for different purposes. In a room-and-pillar system, a heading or entry is a permanent or semi-permanent passageway excavated in the stratum of mineral being mined, thereby to provide passageways for the transportation and travel of men and materials and for passage of air for 25 ventilation. These entries or headings are maintained and protected by barriers or pillars of coal on each side of them which remain in place until the entry or heading is to be abandoned. Rooms, on the other hand, are the first workings to penetrate the body of mineral which is 30 to be entirely extracted. They are haul-ways only by reason of the extraction of mineral in the process of their formation, and are to be used as such only for the extraction of the mineral immediately adjoining to them. Following 35 the complete removal of the mineral, they are destroyed by roof falls and abandoned serving no purpose in connection with the development of the property. Thus the characteristics of 40 rooms differ greatly from entries or headings. Entries are usually driven tight; that is, they are only wide enough to permit a safe haulway to be established and maintained. This affords a measure of safety. They are likewise 45 made high enough to facilitate rapid movement

of men and materials. They are clear of obstructions and conform to certain laws governing the safety and health of the miners. Rooms, on the other hand, are usually of a much greater width. Refuse, is thrown to one side and 5 remains therein. Only coal is removed if it is possible to do so. They serve to subdivide a larger block of coal in its complete extraction to recover coal in a small area embraced by the room itself and a pillar on either side usually 10 having no connection with the recovery of coal elsewhere, not immediately adjoining it.

Parallel entries through a panel or body of coal is as old as coal mining. Rooms parallel to the heading with which the rooms are first in contact and through which first flows the coal produced in the rooms as it is transported toward the surface, is a new departure in mine plans and constitutes a feature of the present invention. The co-extensive-room system with mechanical conveyors is more fully disclosed in the accompanying drawings wherein

15 Figure 1 is a diagram of a mining operation utilizing the present invention.

Figure 2 is an enlargement of the conveyer arrangement which shows the use of loading machines and face conveyers as a part of the system.

Figure 3 is a side elevation in diagram of a shuttle conveyer, showing its relation to the sectional conveyer in a cross-cut and to the loading machine.

Figure 4 is a plan view in diagram of the structure shown in Figure 3.

Figure 5 is a diagram showing successive stages of pillar "slabbing".

Figure 6 is a diagram showing a method of "open-ended" pillar extraction.

Figure 7 shows a heading stump and entry pillar, the chain pillar to be drawn from the next lower entry.

Figure 8 is a similar view showing the chain pillar to be drawn therewith.

Figure 9 is a similar view showing a double-entry symmetrical on both sides.

45 In Figure 1, 1 is a main entry or haulway leading from the surface to the mineral being extracted. 2 and 3 are two of any number of parallel headings thereto in a multiple entry system. The purpose of heading 2 is to form a passage for the conduct of the ventilating air current of the mine. Heading 3 is a travelling way for men.

50 4, 5 and 6 are haulways, air-course and water-course respectively, of a cross entry turned off the main entry 1 at any convenient angle. Entry 6 is dotted to indicate that it can be omitted or

included as conditions warrant. Other parallel entries to 4 can be driven below entry 6.

7 to 15 inclusive are transverse cross-cuts equally spaced along the heading and parallel to each other. Cut 7 is the only one to be driven between entry or heading 4 and a cross-entry or watercourse 16 remote therefrom before the rooms are turned. All the other cross-cuts 8 to 15 are turned off the heading and driven through 10 the heading stump to the line of the room 17 nearest to the heading but no farther. Thereafter the cross-cuts are advanced step-by-step, the section between rooms 17 and 18 being driven from room 17, the section between rooms 18 and 15 19 being driven from room 18, etc. These transverse cross-cuts may taken any convenient angle to the cross-entry 4.

Rooms 17 to 26 inclusive are parallel to each other and to the cross-entry 4. All of them are 20 first turned from transverse cross-cut 7 and are advanced along lines parallel with the cross-entry 4 into the solid coal, with their faces in line, until three transverse cross-cuts are completed, after which the pillar extraction may begin. The 25 faces of the rooms continue to advance at one end in line abreast and the pillar extraction at the other end of each room will proceed at the same rate of speed so that the faces of the pillars are maintained in line abreast.

30 At all times there must be not less than three transverse cross-cuts complete and open for use between the faces of the advancing rooms and the faces of the retreating pillars 27 to 36 which are the ones being extracted. This differs from the 35 ordinary room-and-pillar system in which the face of the room is advanced in one direction and the face of the pillar retreats in the opposite direction. The retreating pillars 27 to 36 inclusive are shown as being extracted by the "sump and wing" method. However any recognized means 40 of pillar extraction can be used. Figure 5 shows progressive stages of "slabbing" the pillar 36a. Figures 2 and 6 show at 36b the well-known "open-ended" pillar extraction.

45 37 is a sectional collecting conveyer mounted on wheels 38 which roll on the rails of a mine track 39 in one of the cross-cuts. It traverses all of the rooms 17 to 26 and has its discharge end located in cross-entry 4, where it transfers its material to 50 mine cars 40 or other means of conveyance.

On either side of conveyer 37 are superposed shuttle conveyers 41 and 42, each made up of an upper section 43 and a lower section 44. 45 indicates a loading or gathering and elevating 55 machine of the type shown in the co-pending application of Ernest P. Jaggard, Serial Number 631,566, positioned to discharge material onto conveyers 41 and 42. Figure 6 shows the use of portable face conveyers in connection with conveyers 41 and 42.

60 Figures 3 and 4 show side and top elevations of the sectional transverse conveyer 37 in its relation to the shuttle conveyers, 44 is the lower of two sectional and extensible wheel supported 65 conveyers on a mine track 46, with its discharge end positioned to deliver material to conveyer 37. 43 is the upper of two sectional and extensible conveyers mounted on wheels on a mine track. The wheels of the two sections are indicated at 47. A part of section 43 straddles section 44, so that the sections can be moved longitudinally of each other independently yet positioned to transfer material from one to the other. 70 The length of the overlapping sections 43 and 75

44 will be at least as great as the distance between transverse cross-cuts 7, 8, etc.

The carriage of the loading machine 45 herein before referred to is indicated at 49, and this machine has a floating conveyer 48 thereon for receiving material from the gathering and elevating means.

The method of pulling the entry pillars, after the block has been worked out and the entry is ready to go on the retreat, has been illustrated 10 in Figures 7, 8 and 9.

In each of the figures mentioned the entry pillars 50 (meaning the group) are split at 51 and extracted after the same general scheme 15 employed to mine the block.

In the present system the width of the entry pillars as well as the width of the rooms and the room pillars will have definite relationships. As it will be necessary to advance the room faces 17 to 26 inclusive at the same pace, the pillar faces 20 27 to 36 inclusive (Fig. 1) are retreating across the block, the time spent to advance a single room unit distance must equal the time spent to retreat the room pillar a unit distance. To accomplish this there will be a relationship between 25 the width of the room and the width of room pillar which will be controlled by and be a factor of

1—the roof conditions,

2—the labor conditions.

30 For example, the roof conditions may permit the use of mechanical loading machines in the advancing room but preclude their use in the pillars. The greater capacity of the machines in tons per minute over other methods of loading 35 coal might dictate a wide room and a narrow pillar.

Should roof conditions allow pillars to be drawn open-ended or slabbed, the extraction will proceed at a more rapid rate than would be true 40 if they were extracted by the sump and wing method. Compensation for the different speeds of loading would be made by altering the relationship between width of room and pillar.

Again, a narrow room may require practically 45 no timbering which would dictate, in the cause of economy, a relatively wide pillar which at the same time might permit loading out the pillar from both sides of the room. That in turn might cause pillar extraction to be carried on in every 50 other room, or second room.

The relationship between width of room and width of pillar would doubtless be changed to meet underground conditions as they are encountered. For any set of conditions, however, 55 the proper relationship once established will continue throughout the block or entry for its full length so long as the conditions persist.

The element of time in mining is a new feature in the development of a plan in which parallel 60 advancing and retreating faces in line abreast, keep pace with each other at a constant distance apart across the block.

This arrangement of rooms and conveyers 65 offers great advantages over other methods of mining.

It first concentrates a large tonnage production in a small area. It lessens the cost of heading development by increasing the tonnage hauled through the cross-entries; for the number of rooms on one side of a cross-entry is only limited by the limit of operating efficiency of the transverse conveyer 37. The same room development can be made on both sides of the cross-entry. This greatly increases the scope of ter- 70 75

rietary served by one cross-entry over the territory thus served in the other types of development enumerated at the beginning of my description.

5 It increases the efficiency in the use of mechanical conveyer; for to use Figure 1 is an illustration, as the pillars are drawn to close cross-cut 10, the cross-cut 13 is completed. Conveyer 37 then is ready to be moved to cross-cut 12. In 10 the meantime, this cross-cut 12 has been cleaned and track laid therein to receive the sections of conveyer 37. When the move is to be made, all of the lower sections 44 of the shuttle conveyers are retracted below sections 43 the full distance 15 between cuts 11 and 12 by simply rolling section 44 along its track. No disassembly of them takes place. Conveyer 37 is torn apart and rolled into cross-cut 11 by rolling its sections on a track, then reassembled. Lower sections 44 of conveyers 20 42 serving the pillars, are rolled forward from cross-cut 11 to cross-cut 12 positioned to again discharge material into conveyer 37.

This plan avoids the daily interruption of work in the rooms to add sections to an extensible conveyer of the usual type. In reality it reduces the task of moving a great length of conveyer, as the transverse conveyer only is torn down and there is but one heavy motor driven discharge end to move. If the ordinary type of sectional room conveyers were in the rooms there would be in addition as many heavy discharge ends to move as there are room conveyers. In the operation illustrated that would mean the moving of twenty discharge ends from cut 11 to cut 12. That would be an extensive task.

Another advantage lies in the ease with which supplies and materials can be taken to or from the working faces.

Another advantage lies in the concentration at one point on the cross-entry of all of the tonnage to be transferred from conveyer to car.

What is claimed is:

1. The method of mining coal which includes the steps of driving rooms along lines parallel with the entry and with their advancing ends substantially abreast and their retreating ends substantially abreast, providing parallel cross-cuts common to all of the rooms whereby ingress and egress and haulage of material are permitted, advancing the rooms and extracting the pillars synchronously to maintain the rooms at approximately the same constant length whereby straight line telescoping conveyers can be used in the rooms, and connecting the rooms to each other and to the entry by another cross-cut every time the rooms advance a distance equal to the space between previously formed cross-cuts, whereby a collecting conveyer can be transferred from one cross-cut to the next adjoining cross-cut every time a new one is formed, and the telescopic conveyers can be so positioned in the rooms as to discharge material upon the transverse collecting conveyer.

2. The method of mining which includes the formation of an entry through the mineral to be mined, by driving parallel headings, aircourses and watercourses and manways of any desired number interconnected with equally spaced and parallel cross-cuts to form straight continuous connections therebetween, projecting said cross-cuts into the mineral beyond the limits of the entry, on either side or both, a distance equal to the distance between the entry and the projected course of a parallel room which will later be joined to the entry, thereafter forming a series

of any desired number of rooms parallel and adjacent to the entry, by advancing all of the rooms in the series substantially at the same speed with their advancing faces abreast, and extracting the pillars at the retreating ends of all of the rooms of the series simultaneously and substantially uniformly at substantially the same speed as the speed at which the rooms are advanced whereby the coal is removed from the pillars before deterioration by crushing and whereby the rooms are maintained at a substantially uniform length during the said advance, and maintaining not less than three equally spaced parallel cross-cut connections between rooms during the advance thereof for ingress, egress, ventilation, drainage and haulage of material.

3. A method of mining coal which permits simultaneous advancement of room and extraction of pillars, which includes the steps of driving an entry haulway thru the stratum to be mined, advancing rooms abreast into solid coal on one side of the entry, parallel to the entry and parallel to each other, connecting the rooms to each other and to the entry haulway by straight line cross-cuts driven to the rise from room to room and between room and haulway, whereby the room entry will be at a higher elevation than rooms contiguous thereto, said cross cuts being substantially parallel to the line of advance of the rooms, advancing all of the rooms and forming additional cross-cuts, equally spaced as the rooms advance, each successive cross-cut constituting the avenue thru which material is transported from rooms to entry haulway as each new cross-cut is completed, and then extracting the pillars between the rooms at the retreating ends of the rooms, in the direction of advance, as the rooms advance, thereby to maintain a pillar line substantially parallel to the advancing faces and cross-cuts, and the rooms, cross-cuts and entry being driven to the rise whereby driving to the dip is eliminated during excavation, and self-drainage of all working places is insured.

4. A method of mining in a pitching seam which includes the steps of driving an entry haulway thru the stratum to be mined, advancing rooms abreast into solid coal on one side the entry, parallel to the entry and parallel to each other, connecting the rooms to each other and to the entry haulway by straight line cross-cuts driven to the rise from room to room and between room and haulway, said cross cuts being substantially parallel to the line of advance of the rooms, advancing all of the rooms and forming additional cross-cuts, equally spaced as the rooms advance, each successive cross-cut constituting the avenue thru which material is transported from rooms to entry haulway as each new cross-cut is completed, and then extracting the pillars between the rooms at the retreating ends of the rooms, in the direction of advance, as the rooms advance, thereby to maintain a pillar line substantially parallel to the advancing faces and cross-cuts, and the rooms at substantially uniform length, all of the rooms, cross-cuts and entry being driven to the rise whereby driving to the dip is eliminated during excavation and self-drainage of all working places is insured.

5. A method of mining in a pitching seam which includes the steps of driving an entry haulway thru the stratum to be mined, advancing rooms abreast into solid coal on one side the entry, parallel to the entry and parallel to each

other, connecting the rooms to each other and to the entry haulway by straight line cross-cuts driven to the rise from room to room and between room and haulway, said cross-cuts being substantially parallel to the line of advance of the rooms, advancing all of the rooms and forming additional cross-cuts, equally spaced as the rooms advance, each successive cross-cut constituting the avenue thru which material is transported from rooms to entry haulway as each new cross-cut is completed, and then extracting the pillars between the rooms at the retreating ends of the rooms, in the direction of advance, as the rooms advance, thereby maintaining the faces parallel and at the same distance apart, whereby, through the use of a conveyer system, the recovery of the room pillars is expedited without sacrificing safe working conditions. 5

CHARLES R. HUGHES. 10
